UNITED STATES PATENT OFFICE.

HEINRICH JOTZEN, OF BARMEN, GERMANY.

DEVICE FOR CLEANING THE FELT OF PAPER AND CARDBOARD MAKING MACHINES DURING THEIR OPERATION.

Application filed February 6, 1923. Serial No. 617,420.

To all whom it may concern:

Be it known that I, HEINRICH JOTZEN, a citizen of the German Empire, residing at Barmen, Germany, have invented certain new and useful Improvements in Devices for Cleaning the Felt of Paper and Cardboard Making Machines During Their Operation, for which I have filed applications for Letters Patent in Germany, Dec. 5, 1921; 10 Austria, Feb. 14, 1922; Czechoslovakia, March 24, 1922; France, Dec. 5, 1922; Switzerland, Dec. 5, 1922; England, Dec. 5, 1922; Netherlands, Dec. 5, 1922, and of which the following is a specification.

15 My invention relates to a device for cleaning the endless felt of paper- and cardboard-making machines during the operation of the machine. In the known devices of this kind the felt is conducted over guide rollers and through a cleaning liquid, the latter being kept in motion by means of a rotating paddle wheel. Hitherto the paddle wheel has always been located on the operative side of the felt and has there functioned in this 20 way, that a portion, it is true, of the pulp or dirt particles is washed away, but another portion is pressed more deeply into the felt. This drawback is obviated by the present invention in that the felt is conducted in the liquid to pass under the paddle wheel in such manner that the felt is guided at some distance from said paddle wheel around the latter, while facing said wheel with its back side.

25 In that way, as experiments have proved, the felt is subjected to a very effective and beneficial cleaning this being probably due to the fact that, owing to the action of the paddle wheel, the liquid is pressed through the felt from its rear side, whereby all particles of dirt are driven out of it.

Conveniently a number of such paddle wheels are provided, each arranged in a separate compartment of the liquid container and the felt is conducted successively through the several compartments in counter-direction to the cleaning liquid. The result is that the felt comes into contact with liquid which is the cleaner the further the 30 cleaning of the felt has progressed, so that the cleaning of the felt may be carried out more perfectly than heretofore, while, nevertheless, the consumption of cleaning liquid is diminished.

35 The accompanying drawing shows dia-

grammatically an embodiment of the invention, by way of example, and represents a vertical transverse section of the apparatus.

In this drawing, *a* indicates the endless band of felt, of which only the portion in the vicinity of the cleaning device is shown, the operative side of the band being below as indicated on the drawing by the dotted line adjacent to the band. *p* is a trough supplied with cleaning liquid. This trough is bisected by means of a vertical partition *h*, and in each of the two compartments so formed a paddle wheel *i*, *k* rotating in the cleaning liquid is mounted. *b*, *c*, *d*, *f*, *g* are guide rollers for the felt to be cleaned. Three of these rollers, *b*, *d*, *g*, are located above the trough *p*, while two of them, *c*, *f* are mounted within the trough, and each below a paddle wheel *i*, *k*, respectively. Thus the felt is guided successively through the two compartments of the trough *p* and underneath the two paddle wheels *i*, *k* in such a manner that the felt *a* faces the paddle wheels with its back side. At the same time, the guide rollers *b*, *c*, *d*, *f*, *g* are so arranged with respect to the paddle wheels *i*, *k* that the felt does not touch said wheels, or with other words, the felt is conducted at some distance from the paddle wheels around each paddle wheel. In consequence thereof, the felt *a* is not directly acted upon by said wheels *i*, *k*. On the contrary, by the rotation of the paddle wheels, the wheels drive the cleaning liquid against the felt and from said non-operative side through the felt itself. In this manner all particles of the pulp or dirt which fill the pores of the felt at the operative side of the latter are thoroughly driven out of the felt and then washed away.

Above the right half of the container *p* is arranged the feed pipe *m* for the cleaning liquid, so that the latter acts first of all on the felt after its former cleaning in the left half; thereupon the liquid passes over the partition *h*, which serves as overflow, into the left half of the container. Thence the liquid again flows alongside the band *a* and counter to its direction of movement, and then overflows the lower-level edge *n* of the trough, a further feed pipe *r* being provided if desired in order to augment the former liquid, this fresh liquid being driven by the paddle wheel through the felt. By this distribution of flow the largest portion of the

dirt can be carried away as it was in the first trough portion, over the overflow edge *n* without first contaminating the liquid already in the trough. Moreover, near the 5 bottom of the left trough portion, and if desired of the right portion also, a discharge cock *o* is fitted and this can be made more or less operative during the working of the apparatus in order to prevent an accumulation 10 of dirt in the trough bottom.

I wish it to be stated that my invention is not restricted to the exact constructional form shown and described, for many alterations and variations may suggest themselves 15 to those skilled in the art without departing from the spirit of my invention as pointed out in the claims.

Claims:—

1. In an apparatus for cleaning the felt 20 in paper and cardboard-making machines during their operation, in combination: a container for the cleaning liquid, a paddle wheel mounted in said container and adapted to rotate in the cleaning liquid, a number 25 of guide rollers for guiding the felt to be cleaned through the cleaning liquid, said rollers being partly mounted above said liquid container and partly within the latter and at a lower level than said paddle wheel 30 and being at the same time so arranged with respect to said wheel that the felt is guided at some distance from said paddle wheel around the latter, while facing said wheel with its back side.

2. In an apparatus for cleaning the felt 35 in paper and cardboard-making machines during their operation, in combination: a container for the cleaning liquid, a plurality of paddle wheels mounted in said container and adapted to rotate in the cleaning liquid,

a number of guide rollers for guiding the felt to be cleaned through the cleaning liquid and round each of said paddle wheels, 45 said rollers being so arranged with respect to the said paddle wheels that the latter face that side of the felt which is the reverse of the operative side, means for feeding the cleaning liquid to that end of the container at which the felt leaves the latter and an overflow at the opposite end of said container. 50

3. In an apparatus for cleaning the felt of paper- and cardboard-making machines during their operation, in combination: a container for the cleaning liquid, said container being divided into a number of compartments, a number of paddle wheels mounted each in a said compartment and adapted to rotate in the cleaning liquid, a number of guide rollers for guiding the felt to be cleaned successively through the said compartments of the said container, said guide rollers being mounted partly above 60 said container and partly within the compartments of the latter at a lower level than said paddle wheels and being at the same time so arranged with respect to said wheels that the felt is guided at some distance from each paddle wheel around said paddle wheels, while facing the latter with its back 65 side, means for feeding the cleaning liquid to that compartment at which the felt lastly leaves said container, an overflow between each two adjoining compartments of said container and an overflow at the outer wall 70 of that compartment at which the felt first enters the said container. 75

In testimony whereof I affix my signature.

HEINRICH JOTZEN.
